UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-REPLENISHING MECHANISM.

1,369,473.

Specification of Letters Patent. Patented Feb. 22, 1921.

Application filed January 28, 1919. Serial No. 273,671.

To all whom it may concern:

Be it known that I, EPPA H. RYON, a citizen of the United States, residing at Waltham, in the county of Middlesex and State 5 of Massachusetts, have invented a new and useful Weft-Replenishing Mechanism, of which the following is a specification.

This invention relates particularly to improvements in weft replenishing mechanism 10 of the general type disclosed in my prior application, Serial No. 244,637, filed July 12, 1918.

In this prior application I have shown a weft detector mounted independently of the 15 lay and engaging the weft carrier through the open upper side of the shuttle. In the preferred form the detector was mounted on the transerrer and was moved toward the shuttle on each alternate beat of the lay. 20 The detector was normally held yieldingly in operative position relative to the transerrer and had a detecting action on every downward stroke of the transerrer, including the stroke by which a fresh weft carrier 25 was inserted in the shuttle. Detecting action during the first part of the transferring stroke has been found undesirable, as the engagement of the fresh weft carrier by the detector during the first part of the movement 30 of the weft carrier from the magazine toward the shuttle may cause displacement of the weft carrier or an incorrect indication of weft exhaustion by the detector.

It is the general object of my invention to 35 provide a construction in which the weft detector is normally in inoperative position relative to the transerrer and in which the effective action of the weft detector occurs after the transerrer has partially performed its downward movement.

Another object is to provide means by 40 which a detector mounted upon and movable with a transerrer may be moved at a greater speed than the transerrer during a 45 portion of the detecting stroke.

To the attainment of these objects in the preferred construction, I provide means, such as a lever mounted on the transerrer, by which the detector may be advanced to 50 detecting position during the latter part of the downward movement of the transerrer. Such advance movement of the detector and lever may conveniently be caused by engagement of said lever by a relatively fixed stop.

My invention further relates to arrangements and combinations of parts which will be hereinafter described and more particularly pointed out in the appended claims.

A preferred form of my invention is shown in the drawings, in which—

Figure 1 is a front elevation of a portion of a magazine embodying my invention;

Fig. 2 is a similar view, partly in section, and showing certain parts in a different position;

Fig. 3 is a side elevation of a portion of the magazine;

Fig. 4 is a detail elevation looking in the direction of the arrow 4 in Fig. 3;

Fig. 5 is a sectional view taken along the 70 line 5—5 in Fig. 3, and

Fig. 6 shows certain of the parts in Fig. 1 at the beginning of transfer.

Referring particularly to Figs. 1 and 2, I have indicated a magazine frame 10 to 75 which a frame member 11 is rigidly secured in spaced relation. A transerrer 12 is pivoted on a stud 13 fixed in the magazine frame 10, said transerrer being actuated on every alternate beat of the lay through a 80 link 14 (Fig. 3) from driving mechanism not shown.

A pin or rod 15 is slidably mounted in horizontal position in the transerrer 12 and normally occupies the position shown in 85 Figs. 1 and 2. When moved to the left by the weft detecting mechanism, the rod 15 engages a cam 16 (Figs. 3, 4 and 5) as the transerrer rises, thus swinging an arm 17 about its pivot 18 and operating suitable 90 mechanism through the segmental gear 19 to release a weft carrier W so that it may advance to transfer position.

All of the parts thus far described are 95 essentially similar in construction and operation to the corresponding parts in my prior application. I have, however, omitted the spring shown in my earlier application for holding the rod 15 normally to the right and have provided instead a cam surface 100 20 (Fig. 4) on the arm 17. As the transerrer rises the rod 15 first engages the cam 16 and moves the arm 17, and as it continues to rise thereafter engages the cam 20 and is restored to normal position in which 105 it remains until moved therefrom by weft detecting mechanism to be now described.

This weft detecting mechanism comprises

a detector 21 pivoted at 22 in the fork of a lever 23 which in turn is pivoted at 24 to the transerrer 12. The lower end of the detector is commonly provided with teeth or 5 otherwise roughened. A light spring 25 between the transerrer 12 and the lever 23 normally moves the lever and detector upwardly until the offset upper end 26 of the detector 21 engages a stop 27 formed on the 10 arm of the transerrer 12. The lever 23 extends to the right beyond its pivot 24 and is at times engaged by a yielding stop 28 pivoted at 29 to the magazine frame member 11. A relatively heavy spring 30 inter- 15 posed between the frame member 11 and an arm 31 of the stop 28 yieldingly moves the stop 28 upwardly until an adjusting screw 32 thereon engages a lug 33 on the frame.

The parts are shown in normal position 20 in full lines in Fig. 1 with the detector 21 raised to inoperative position relative to the transerrer 12. The parts remain in this position until the transerrer is drawn downward by the rod 15. Continued downward movement causes the lever 23 to engage the stop 28 by which it is swung about its pivot 24, thus advancing the detector 21 to engage the weft carrier W.

If a well-filled weft carrier is engaged, 30 as shown in Fig. 2, the teeth on the end of the detector will engage the weft and the detector will be held in the upright position shown in Fig. 2, in which position it clears the sliding rod 15 previously described. As 35 the transerrer continues to move downward the stop 28 will yield to permit downward movement of the lever 23 as is also indicated in Fig. 2.

When, however, the detector engages a 40 substantially exhausted weft carrier, the end of the detector slides along the weft carrier to the position shown in dotted lines in Fig. 1, and during this movement of the detector the upper end thereof acts as a cam 45 upon the rod 15, sliding the same into position to engage the cam 16 on the arm 17 (Fig. 3). The time of action of the detector may be varied by adjustment of the stop 28 by the screw 32.

50 It will be noted that the movement of the detector, after the lever 23 engages the stop 28, is more rapid than the movement of the transerrer upon which the detector is mounted. This enables the detector to maintain effective contact with a fresh weft carrier during the latter part of its transfer movement and prevents false indication of weft exhaustion.

With this arrangement of parts, it will be 60 seen that the detector is not advanced to engage the weft carrier until the transerrer has partially performed its downward movement. Time is thus provided during which the transerrer, on the occasion of transfer, 65 can advance the fresh weft carrier into en-

gagement with the exhausted weft carrier before the fresh carrier is engaged by the detector and possibly displaced thereby. It is found that this construction is very efficient in preventing displacement of the 70 fresh weft carrier during transfer, and also in preventing incorrect indication of weft exhaustion by a detecting movement executed while the fresh weft carrier is in initial transit. The parts just prior to transfer are shown in Fig. 6.

Having thus described my invention, it will be evident that changes and modifications can be made therein by those skilled in the art without departing from the spirit 80 and scope of my invention as set forth in the claims, and I do not wish to be otherwise limited to the details herein disclosed, but what I claim is:-

1. In a weft replenishing loom, in combination, a magazine, a transerrer, a detector movable therewith, and means to give said detector an additional movement relative to said transerrer as the latter descends.

2. In a weft replenishing loom, in combination, a magazine, a transerrer, a detector mounted on said transerrer and normally held in inoperative position thereon, and means to advance said detector to operative position as said transerrer descends.

3. In a weft replenishing loom, in combination, a magazine, a transerrer, a member movably mounted on said transerrer, a detector movably mounted on said member, and means to move said member and detector relative to said transerrer as the latter descends.

4. In a weft replenishing loom, a transerrer, a member yieldingly mounted on said transerrer, a detector pivoted to said member and normally held in inoperative position, and a yielding stop positioned to engage said member as said transerrer descends and to thereby advance said detector to operative position.

5. In a weft replenishing loom, in combination, a magazine, a transerrer, a lever pivoted to said transerrer, a weft detector pivoted to said lever, a stop for said detector fixed on said transerrer, yielding means to hold said detector normally against said stop, and a yielding device on said magazine effective to engage said lever as 115 said transerrer descends to thereby give said detector a detecting movement.

6. In a weft replenishing loom, in combination, a magazine, a transerrer, a weft detector mounted thereon, a rod freely slideable in said transerrer and movable from normal position by said detector upon substantial exhaustion of the active weft carrier, transfer indicating mechanism operable by said rod after such movement thereof 120

by said detector, and means to restore said rod to normal position.

7. In a weft replenishing loom, in combination, a magazine, a transerrer, a weft detector mounted thereon, a rod freely slideable in said transerrer and movable from normal position by said detector upon substantial exhaustion of the active weft carrier, and a transfer-indicating arm movable by said rod when thus positioned by said detector, said arm having a cam surface thereon effective to restore said rod to nor-

mal position during continued upward movement thereof.

8. In a weft replenishing loom, in combination, a magazine, a transerrer, a detector movable therewith, and means to advance said detector more rapidly than said transerrer, during a portion of the transferring movement thereof. 15 20

In testimony whereof I have hereunto affixed my signature.

EPPA H. RYON.
